UNITED STATES PATENT OFFICE

134,167

DESIGN FOR A DOUBLE BOILER OR THE LIKE

Karl Schneider, Chicago, Ill., assignor to Sears, Roebuck and Co., Chicago, Ill., a corporation
of New York

Application February 26, 1942, Serial No. 105,998

Term of patent 7 years

To all whom it may concern:

Be it known that I, Karl Schneider, a citizen of Germany, resident of the United States of America, having applied for first citizenship
papers of the United States, residing at Chicago, in the county of Cook and State of Illinois, have invented a new, original, and ornamental Design for a Double Boiler or the like, of which the following is a specification, reference being had to the accompanying drawing, forming a part thereof.

Figure 1 is a top plan view of a double boiler
or the like embodying my new design;

Figure 2 is a side elevational view of the same;
and

Figure 3 is a fragmentary side elevational view
thereof taken at an angle of 90° from Figure 2,
to illustrate the lip.

I claim:

The ornamental design for a double boiler or the like, as shown and described.

KARL SCHNEIDER.
